MECHANICAL TELEPHONE SWITCHING SYSTEM

Filed May 17, 1919

INVENTOR

Frank M. Slough

UNITED STATES PATENT OFFICE.

FRANK M. SLOUGH, OF ELYRIA, OHIO, ASSIGNOR TO STROMBERG-CARLSON TELEPHONE MANUFACTURING COMPANY, OF ROCHESTER, NEW YORK, A CORPORATION OF NEW YORK.

MECHANICAL TELEPHONE SWITCHING SYSTEM.

Application filed May 17, 1919. Serial No. 297,949.

To all whom it may concern:

Be it known that I, FRANK M. SLOUGH, a citizen of the United States, residing in Elyria, county of Lorain, and State of Ohio, have invented certain new and useful Improvements in Mechanical Telephone Switching Systems, of which the following is a full, clear, concise, and exact description.

My invention relates to that class of telephone systems commonly known as "mechanical telephone switching systems," wherein under the control of a subscriber's substation controlling means, central office switching devices are directed to complete any desired connection with a called-for telephone line of a plurality of such lines.

More specifically my invention relates to improved controlling means for such switching devices, by the use of which the switching devices may be controlled from the subscriber's telephone instrument with certainty and with a minimum of inexpensive apparatus.

An object of my invention is to control all of the operations of such a switch by a single relay operating under substation control, the said relay having a plurality of armatures operating when the relay is energized successively, there being a definite time interval between the actuation of the first armature and the actuation of the second armature.

I have in the system of my invention so organized the apparatus of such a switching device, that other objects of my invention involving other subordinate functions of the devices are attained. These will be made more apparent from the description of the telephone system which embodies my invention, and a drawing of which accompanies this specification.

In this drawing, at A I show a substation of a calling one of a plurality of telephone lines, a called telephone line of which has a substation illustrated at B. At C I show a central station line interconnecting link circuit having incoming circuit conductors 2, 3 and 4, and outgoing terminal switch wipers 5, 6 and 7.

I do not show the switching means and switch contacts, whereby the calling telephone line having the substation A, is connected to the link circuit C, since this is immaterial so far as my present invention is

concerned and I may employ any of the well known means for accomplishing this interconnection.

At IMP, I show an impulse relay adapted to be controlled by the subscriber's substation apparatus at A, to operate the electro-mechanical switching means associated with the link circuit C, as will be later described. The relay IMP contains two armatures, the one shown at 8 being a fast operating armature, and the one shown at 7 being a slow responding armature; the armature 7 is also given a relatively insensitive adjustment as compared with the armature 8. Thus, the armature 8 will operate with lesser current strengths through the magnet of the relay IMP, and will operate on current impulses of shorter duration.

The wipers 5, 6 and 97 are connector switch wipers, and are adapted when moved under the control of a primary stepping magnet PM and a subsequently operating secondary stepping magnet SM to connect with terminals, such as the terminals 9, 10 and 11 of the called line as, for instance, the line having the substation apparatus, illustrated at B. The said wipers 5, 6 and 97 are first carried step by step in a primary direction under the propelling influence of the primary magnet PM, and afterwards propelled in a secondary direction under the influence of the secondary stepping magnet SM, to locate, first the group in which the called line terminals are located, and second to locate the said terminals in this group.

Associated with the connector switch mechanism and controlling the same, is a steering switch having a propelling magnet SSM and having a plurality of wipers W¹, W², W³, W⁴, and W⁵, these wipers each engaging separate contact banks, over which they are moved, when the steering switch magnet is deenergized under the initial energization, the action of the steering switch magnet being to always advance the wipers in the same direction upon each deenergization of the said magnet. The steering switch preferably has its bank contacts arranged in an open arc, and the wipers are preferably constructed having a plurality of contact points disposed at different angles from the supporting rotating shaft, the arrangement being such that immediately after one finger of a wiper leaves the last contact in a row

of contacts, that another finger of the said wiper will engage the first contact of the bank. Thus, the effect is produced by a single wiper finger moving from contacts arranged in a complete circle, the advantages of an open arcuate contact bank structure however being secured. Such a switch structure is old in the art however, being illustrated in a patent to Clement, No. 1,107,153, 10 patented August 11, 1914.

At RM, I show a release magnet for the connector switch, a controlling release relay being shown at RR, a common interrupter Cf for a plurality of connector switches being provided to control the operation of the 15 said release relay and the said release magnet, as will be later made apparent from the description of the operation which follows.

A ringing relay is shown at RG, and a 20 ringing trip relay at RT. A switch relay SR is provided for the purpose of altering the connections from the ringing generator G, for a purpose later to be described. A source of busy tone current is shown at BZ, 25 and may be common to a plurality of connector switches, as may also be the case with the generator G and the central exchange battery BY, illustrated in the drawing at various places, but which may be in 30 effect and usually would be, a single battery. Off normal contacts PON are illustrated at various points in the drawing, and control various circuits for the performance of various functions, as will be later understood 35 from the description of the operation of the system which follows.

These contacts are all shown as being normally open and they will be understood as being closed immediately when the connector switch is moved from normal position. 40 Other off-normal contacts are shown at SON and are normally open contacts, but are closed only when the connector switch takes its first step in a secondary direction. A 45 double wound impedance coil IC is shown through the windings of which talking battery for the called substation transmitter is fed, talking battery being fed through the windings of the impulse relay IMP and 50 the impedance coil AC, to the substation transmitter at the substation A on the calling line.

The system of my invention operates, as 55 follows: The subscriber at A, initiates the call by taking his receiver from the hook and thereby closing the hook switch contacts 12, so that the circuit of the line conductors of the calling line are made continuous, and the line-link circuit interconnecting means 60 is made operative to extend the circuit of the line conductors to the conductors 2 and 4 which are the talking strands of the link circuit C. A test conductor 3, normally open at the connector switch C, is for the 65 purpose of causing the link circuit to test

idle, and therefore to be seized by the calling line-link circuit interconnecting apparatus, not specifically illustrated in the drawing but understood. This connector switch mechanism is illustrated as of that type 70 wherein the absence of potential on the test wire, such as the conductor 3, enables the link circuit to be seized by incoming calling lines, and the presence of potential, such as ground battery potential, prevents such seizure and is placed on the said conductor 75 after such a seizure to guard the trunk from intrusion by other calling lines. This last named action immediately takes place as will now be described.

The telephone line conductors being extended to the talking strands 2 and 4 of the link circuit, a circuit is completed for the flow of battery through the impedance coil winding AC and the winding of the impulse relay IMP, the said circuit comprising the line conductors in series and the talking set at the substation A, as well as the substation sender S and the serially included resistance coil RC, which is, however, at this time normally shunted by contacts CTS of a ringing key RK; the resistance coil and ringing key being provided for a purpose later to be made apparent.

Current from this circuit will operate the relay IMP, which relay attracting its armatures completes a circuit for the steering switch stepping magnet SSM, this circuit being traced as follows: from the ground pole of battery, through contacts 13 of the armature 8 and contacts 15 of the armature 7, circuit conductor 16, first position contact of the steering switch wiper W², normal contacts 17 of the steering switch magnet, armature 18 thereof, the winding of magnet SSM and the battery BY to the ground pole of battery. Current over this circuit will cause the steering switch magnet to operate its armature 18 until the contacts 17 controlled thereby are opened, whereupon the magnet will immediately retract its armature, and upon such retraction a ratchet pawl carried by the armature 18 will propel the steering switch wipers W¹, W², W³, W⁴ and W⁵ to their second position contacts, whereupon the circuit of the steering switch magnet SSM, just described, is broken by the wiper W², leaving its first position contact. Wiper W³ leaving its first position contact, applies ground potential to the test conductor 3 to guard the trunk circuit C, from intrusion by other calling lines. Wipers 4 and 5 merely move from first to second operative position without performing any other function. Wiper W¹, moving from first to second position, conditions a circuit 110 for the primary stepping magnet PM.

Thereupon the subscriber making the call, 115 will operate his sending dial interrupter S, to interrupt the circuit of the line a given 120

number of times corresponding to the first digit of the called line number. A battery supply circuit which has been traced is thereby interrupted such a given number of 5 times, the impulse relay IMP serially included therein will cause its armature 7 to be retracted during the period when the circuit interruptions are being made, while the armature 8 will respond to such circuit interruptions, it being retracted at each circuit 10 interruption and attracted upon each subsequent circuit closure. Upon each attraction of the armature 8, the armature 7 being continuously retracted, a circuit is completed 15 for the primary stepping magnet PM to operate this magnet, which for each operation will step the connector switch wipers 5, 6 and 97 one step in a primary direction. This circuit is traced as follows:—from the 20 ground pole of battery, through contacts 13 of the armature 8 and normal contacts 14 of the armature 7 of the relay IMP, circuit conductor 17, steering switch wiper W¹ and second position contact thereof, the winding 25 of the primary magnet PM, and the battery BY, to the ground pole of the said battery. Current from this battery, will as has been said, energize the primary magnet PM as often as this circuit is closed, and 30 therefore the connector switch wipers are directed to a point opposite the group in which the called line contacts are located.

When the series of circuit interruptions corresponding to the first digit of the called 35 line have been completed, the slow responding armature 7 of the relay IMP, will again be attracted and a circuit will again be completed for the steering switch magnet SSM. In the meantime, it is to be noted that all of the normally open contacts, shown in the drawing at various places and indicated by the letters PON, have been closed. This second circuit for the stepping magnet SSM, may now be traced:—from the 40 ground pole of battery, through the contacts 13 and contacts 15 of the relay IMP, circuit conductor 16, now closed PON contacts, second position contact and wiper W² of the steering switch, normally closed 45 contacts 17 of the steering switch magnet SS, the armature 18 thereof and winding of the said magnet, and battery BY, to the ground pole thereof. Current flowing over this circuit, will just as in the former case, 50 cause the steering switch magnet to energize, and then breaking its contacts 17 de-energize to propel the steering switch wipers to their third operative position, this since the secondary off-normal contacts SON are 55 still open, breaking the circuit of the steering switch magnet SSM.

The subscriber at A again operating his sending dial interrupter a second time to 60 interrupt the circuit of a calling line a given number of times corresponding to the

last digit of the called line number, will again operate the impulse relay IMP and consequently its armatures in the same way as before, but in this case the secondary stepping magnet SSM replacing the primary stepping magnet PM in the stepping circuit, comprising the conductor 17 which has been previously traced. Since the primary magnet is connected to second position contact and the secondary magnet to third 70 position contact of the steering switch wiper W¹ prior to the actuation of the stepping magnet SSM, no other circuits were operative to produce any operative results by the functions of the different steering switch wipers into their third position. 75

The secondary magnet being actuated a given number of times, will now step the connector switch wipers 5, 6 and 97 in a secondary direction a given number of steps 80 corresponding with the number of circuit closures of the telephone line following line interruptions produced by the dial S.

At the end of the second series of circuit 85 interruptions the relay IMP again attracting both of its armatures will operate the steering switch magnet, the circuit for the said steering switch magnet this time comprising third position contacts of the wiper W² and now closed secondary off-normal 90 contacts SON, the wipers now being propelled into fourth position, and the circuit of the steering switch magnet being broken upon the wiper W² leaving its third position. 95

The subscriber will now depress his substation ringing key RK to open the shunt normally existing about the resistance coil RC, and which resistance coil is thus operatively included in circuit with the line conductors to weaken the energization of the impulse relay IMP, in circuit with the said line conductors. The relay IMP will retract its less sensitive armature 7, a circuit thereupon being closed, if the called-for line 100 is in an idle or unused condition, for the ringing relay RG. This circuit may be traced as follows: from the ground pole of battery, through contacts 13 and contacts 14 of the relay IMP, circuit conductor 17, steering switch wiper W¹ and fourth position contact thereof, circuit conductor 20, winding 21 of the relay RG, connector switch wiper 97, the engaged test contact 11 of the called-for line through a winding 105 COR associated with the called-for line test contacts, of which the contact 11 is a multiple contact, and the battery BY to the ground pole thereof. 110

Current from the battery BY flowing 115 over this circuit will, by traversing the winding, 21, of the relay RG, energize this relay, which will attract its armatures applying ringing current to the called-for line conductors, the ringing circuit being 120 125 130

later traced. Consequently to the operation of the relay RG, the relay 19 will be operated over a circuit including contacts 22 of the relay RG, this circuit being completely traced as follows: from the ground pole of battery, normal contacts 23 of the relay SR, now closed contacts 22 of the relay RG, a second or holding circuit 24 of the relay RG, an energizing winding 25 of the relay 19, and battery BY, to the ground pole thereof.

Current traversing the winding 25, will energize the relay, which energizing circuit will attract its armature, switching circuits as will be later described.

By the operation of the relay RG, a circuit is completed for the flow of interrupted ringing current from the ringing generator G, through the interrupter I, this circuit being traced as follows: from the ground pole of battery, and then alternately through the ringing generator G and the interrupter I, to an interrupter brush 1B, a resistance lamp RL, normal contacts 26 of the relay SR, the shunted winding of the ringing trip relay RT and its shunt in multiple, now closed contacts 27 of the relay RG, connector switch wiper 5 and co-operating called line terminal contact 9, called line conductor 28, condenser 29, bell 30, switch contact 31, called line conductor 32, called line terminal contact 10, and co-operating connector switch wiper 6, now closed contact 33 of the relay RG, resistance coil 37, the battery BY, to the ground pole thereof.

Ringing current, with superposed battery potential from the battery BY, will flow over the said called line circuit intermittently under the control of the interrupter I, until the response of the called-for subscriber. This signaling circuit extending to the called line comprising the serially included winding of the ringing trip relay RT, which upon the response of the called-for subscriber, will operate to disconnect the ringing current source in a manner later to be described.

In the meantime, the relay 19 having been operated, will disconnect the source of busy tone current BZ, by the opening of relay contacts 38 from the talking strand 4, leading to the calling line, and the subscriber after pressing the ringing button to initiate the machine interrupted ringing operation, placing his receiver to his ear will not hear the busy tone and will know that the called-for line is not busy, but is idle, and that the ringing of the called line is commenced.

If the subscriber in haste or through error did not sufficiently press the ringing key RK to open the contact CTS, the busy tone current would not have been removed and the subscriber would get the busy tone and would retire his instrument instead of wait-

ing for the response of the called-for party which would be unavailing, since the called-for party's bell would not be rung in such a case.

The armature of the relay 39 of the relay 19 being operated, will close a locking circuit for the relay 19, comprising consequently closed contacts 40 of the armature 39 and off-normal contacts PON, this locking circuit therefore being under the control of the return to normal switch operation. At the same time greater potential is placed upon the test wiper 97, through the PON contacts and now closed relay contacts 40 and 41 of the relay 19, to guard the called line from being seized by another connector switch which may seek to make connection with the said called line, by causing its wipers to engage multiple terminal contacts of the contacts 9, 10 and 11, expressly illustrated in the drawing. The contacts 42 of the relay RG now being open, the consequent closure of the contacts 18 of the relay 9, will be at this time ineffective.

Upon the response of the called subscriber, a conductive bridge of the called line being accomplished by the closure of hook-switch contacts 43 at the station B, for the flow of direct current over the signaling circuit, which has been before traced, direct current will flow over the said signaling circuit and through the ringing trip relay RT, causing the ringing trip relay to operate its contacts 44, which will establish a short circuit about the holding winding 24 of the ringing relay RG, deenergizing the said ringing relay which will attract its armatures and dissociating the ringing generator from the called-for line, such dissociation being accomplished by the opening of contacts 77 and 33 of the relay RG. The locking contacts 22 for the holding circuit of the relay RG, which comprised the winding 24, are now broken.

When the relay RG was deenergized, the contacts 42 were closed completing a circuit for the steering switch stepping magnet, which circuit may be traced as follows: from the ground pole of battery, through contacts 13 and 15 of the relay IMP, circuit conductor 16, now closed contacts 18 of the relay 19, normal contacts 42 of the relay RG, circuit conductor 45, fourth position contact and wiper W² of the steering switch, normally closed contact 17 of the steering switch magnet SSM, the armature thereof, the winding thereof, the battery BY, to the ground pole thereof.

Current from the said battery will flow over this circuit energizing the steering switch magnet SSM, contact 17, will again retract to propel the steering switch wipers one step to put them in fifth position, whereupon the steering switch magnet circuit will be broken, the wiper W² leaving the fourth

position contact to which is connected the circuit conductor 45, of this energizing circuit.

The subscribers are now in conversational circuit the talking strands 2 and 4 being extended through steering switch wipers W^4 and W^5 and fifth position contacts thereof to the connector switch line wipers 5 and 6, which are in contact with the terminals of 10 the called line conductors. The subscribers' substation transmitters receive battery current as before described, the calling subscriber through the winding of impedance coil AC, and the winding of the impulse relay IMP, and the called subscriber through 15 the windings of the impedance coil IC, condensers 46 and 47 joining the calling and called talking strands. Should the called subscriber after first responding hang up his receiver, he may be recalled by the ringing 20 of his telephone bell 30, by the calling subscriber depressing the ringing key RK; in such a case the bell 30 will be rung for such periods and only during such periods as the 25 ringing key RK may be depressed, the number of rings and the duration of them being thus placed under the control of the calling subscriber after an initial response of the called-for subscriber. This is very desirable 30 in some systems, since the intermittent ringing is annoying and is unnecessary for re-ring purposes.

Reringing by depressing the ringing key RK under such condition is accomplished 35 as follows; the subscriber depressing the ringing key RK, removes the shunt about the resistance coil RC, which being interposed in the line conductors causes the retraction of the armature 7 of the impulse relay IMP. A circuit is thereby closed as follows for the relay SR. From the ground pole of battery, through contacts 13 and 14 of the relay IMP, steering switch wiper W^1 and fifth position contact thereof, the winding 40 of the switching relay SR, the battery BY, to ground pole thereof. Current from this battery will operate the relay SR, attracting its armatures, the contacts 23 and 26 being opened; the contacts 23 being 45 opened prevent a "holding" of the relay RG during the rering period. The contacts 26 being open, the interrupted source of ringing current and the contacts 48 being closed completes an alternating circuit directly 50 from the ringing generator G, through a resistance lamp LR, the circuit from the said generator being extended from the said contacts 48 to the ringing trip relay RT, and through contacts 27 of the relay RG, which 55 is now operated, as will now be described, the circuit extending over the called line and through the subscriber's bell therefrom through the wiper 6, contacts 33 of the relay RG, resistance coil 37, battery BY, to ground. A small proportion of this return- 60

ing ringing current will flow in a by-path comprising steering switch wiper W^4 and its fifth position contact and a winding 50 of the impedance coil IC, and in addition a small proportion of the ringing current will 70 traverse condenser 47, some of it flowing over the calling line conductors through the calling subscriber's telephone set, and back through condenser 46 and winding 51 of the impedance coil IC, to ground. This small 75 amount of ringing current flowing in a by-path through the calling subscriber's telephone set, will audibly apprise the calling subscriber that the ringing of the called subscriber's bell is being accomplished. 80

The relay RG which has been before mentioned as having been operated, was operated upon the closing of the contacts 52 of relay SR, these contacts closing an energizing circuit for the relay RG, this energizing circuit comprising the battery BY, the winding 25 of the relay 19, the winding 24 of the relay RG and the contacts 52 of the relay SR, and the relay RG will be kept operated, barring the response of the called-for subscriber, as long and as often as the ringing key RK is depressed at the calling station. 90

The conversational circuit is re-established each time that the ringing relay RG is restored and the subscribers may converse at any such time upon the response of the called-for subscriber. Upon the termination of the conversation, the subscriber at the station A, may automatically restore the connector switch mechanism to normal position, by placing his receiver upon the hook, opening the contacts 12 serially included in the line circuit, the opening of these contacts restoring the impulse relay armature 8 to normal, whereupon the circuit of the release relay RR is completed, whenever the segment 55 of the interrupter CI makes contact with the brush 57. 100

During the different periods when the subscriber's dial was operated vibrating the armature 8, this circuit may have been momentarily closed, but it is not sufficient to cause the release of the connector switch by the momentary closure of this circuit, since a continued closure of this circuit comprising the contacts 58 of the relay IMP is required for such a period of time as may be necessary for the contact 55 of the interrupter CI, to travel from the brush 57 to the brush 56. 110

However, upon the retiring of the calling subscriber the contacts 58 are closed for a sufficient period for this to take place and the relay RR is first operated by this closure which completes an operative circuit for the relay RR, comprising the contacts 58 of the relay IMP, PON being normal contacts, the winding of the relay RR, normal contacts 60 thereof, interrupter brush 57 and passing 120

115

125

130

contact segment 55 of the interrupter CI, resistance coil 62, and battery BY. Current from the battery will operate the relay RR, breaking the contact 60 in the above 5 circuit, but substituting a circuit conductor 63 leading through a resistance coil 64 to the negative pole of the battery BY for the conductor 65 interrupted by the breaking of the contact 60. The relay RR is maintained 10 operated therefore through the contacts 58 of the relay IMP, for such a period as may be required to cause the segment 55 to contact with the brush 56, whereupon an energizing winding is momentarily closed for 15 the winding 66 of the release magnet RM, through now closed contacts 67 of the relay RR. The release magnet RM being operated, will operatively lock through its consequently closed contacts 68, and off normal 20 switch contacts PON, this locking circuit comprising a second winding 69 of the release magnet RM. At the same time a circuit is completed for the steering switch magnet SSM, comprising switch off normal 25 contacts PON, now closed contacts 70 of the release magnet RM, fifth position a resting steering switch wiper W², normal contacts 17 of the steering switch magnet SSM, the armature and the winding of said magnet, 30 and the battery BY to ground. The steering switch magnet will be energized attracting its armature, thus breaking its circuit by the breaking of its contacts 17, the armature will be again retracted propelling 35 the steering switch wipers from fifth to first, or normal position.

When the connector switch mechanism is completely restored to normal, the PON contacts will all be opened, opening the various 40 controlled circuits and all of the apparatus involved will have been restored to normal. At the same time, the test wire 3 which has had a guarding ground potential connected to it by the switch wiper W³, will have this potential removed when the wiper W³ is in the first or normal position, and line-link interconnecting switching 45 means held operative by the presence of this ground potential will be released to sever the connection previously existing between the calling line and the connected link circuit.

It will be understood that if the subscriber abandons the call before its completion, 55 any of the well known circuit arrangements may be employed to restore the connector switch and its associated steering switch to normal position.

Although I have described my invention 60 as embodied in a specific structure in which I prefer to use it, I am aware that numerous and extensive departures may be made from the said embodiment without departing from the spirit of my invention, and I do 65 not therefore limit my claims to the said

embodiment but define my invention in the following claims:—

1. In a telephone system, a calling telephone line, a called telephone line, sub-station for each of the lines, an automatic circuit interrupter at the sub-station of the calling line, central office switching mechanism for inter-connecting calling and called telephone lines under the control of the automatic interrupters of calling 75 lines, means to associate the said calling line with the said switching mechanism, actuating means for the said switching mechanism adapted to actuate the same under the control of the calling line interrupter, to cause it to make connection between the calling line and the desired called line, a signal bell at the sub-station of the called line, automatic intermittent ringing mechanism associated with the said switching mechanism operative under the control of the said calling line interrupter to initiate the automatic intermittent ringing of the said bell, means associated with the said automatic ringing mechanism to dis- 80 continue the automatic intermittent ringing of the said bell upon the response of the called line sub-station, a ringing relay for the said switching mechanism and means for actuating the same, said means being adapted to be subsequently operated under the control of the calling line sub-station apparatus to cause the subsequent ringing of the called line bell at any time 85 subsequent to the retiring of the called line sub-station apparatus, the said subsequent ringing being independent of the control of the said automatic intermittent ringing mechanism.

2. In a telephone system, in combination 105 with a calling and a called telephone line, of sub-stations for said lines, an automatic dial for each of the said sub-stations, signal bells at each of the said sub-stations and central office switching mechanism for inter-connecting calling and called telephone lines under the control of calling line, automatic dials, means to control the said switching mechanism under the said calling line dial to cause it to inter-connect the said calling and the said called line, machine ringing mechanism associated with the said switching mechanism, a ringing relay associated with the said switching mechanism and adapted to disassociate the said automatic ringing mechanism, from the said switching mechanism, means to operate the said automatic ringing mechanism when the said calling and called lines have been inter-connected by the said switching mechanism, and means to subsequently operate the said ringing relay under the control of the said automatic dial after a first response of the station on the called line, the said ringing relay being adapted to ap- 110 115 120 125 130

ply a continuous source of ringing current to the called line for such periods as may be determined by the said calling line automatic dial.

5 3. In an automatic telephone system, calling and called lines therefor, sub-station apparatus for each of the lines, a connector switch to inter-connect the lines under the control of the calling line sub-station apparatus, a telephone signal bell at the sub-station of the called line, a ringing generator associated with the said connector switch to ring the said bell, a circuit interrupter for the said ringing generator to intermittently ring the said bell, means to first connect the said ringing generator through the said interrupter to the bell of the called line to ring the same intermittently, means responsive to the response of the called station apparatus to discontinue the said interrupted ringing and means responsive to an actuation of calling line sub-station apparatus subsequently to operate said signal bell independent of the said interrupter for such a period as may be determined by the said calling sub-station apparatus.

4. In a telephone system, lines divided into groups, an automatic switch having motion in one plane to select groups and motion in a plane at right angles thereto to select a line in a selected group, means including a relay for controlling the operation of the said switch, a single energizing winding only for said relay, means for energizing the said winding comprising a source of current connected to the said winding over a line circuit, a plurality of armatures for the said relay, means for rapidly interrupting the said line circuit, means whereby one of the said armatures vibrates in response to the said interruptions and means for maintaining the other armature in normal position during the transmission of the said impulses.

5. In a telephone system, lines divided into groups, an automatic switch having motion in one plane to select groups and motion in a plane at right angles thereto to select a line in a selected group, means including a relay for controlling the operation of the said switch, a single energizing winding only for said relay, means for energizing the said winding comprising a source of current connected to the said winding over a line circuit, a plurality of armatures for the said relay, means for rapidly interrupting the said line circuit, means whereby one of the said armatures vibrates in response to the said interruptions and means for maintaining the other armature in normal position during the transmission of the said impulses, a ringing relay associated with the said switch and adapted when operated to project a source

of ringing current over the selected line circuit, a resistance coil in circuit with the said relay winding at the sub-station of the line in circuit therewith, means to include the resistance coil in circuit with the said line to control the said second armature and means responsive thereto to operate the said ringing relay.

6. In an automatic telephone system, the combination with a plurality of telephone lines, one of which is a calling line and another of which is a called line, of substation apparatus for each of the said lines, a connector switch adapted to be associated with the said calling line and controlled thereby to make connection with multiplied terminals of the said called line, a relay for the said connector switch, a circuit for the said relay comprising a source of current, and the sub-station apparatus of the calling line, a pair of independently operable armatures for the said relay, an energizing winding for the said relay included in the said circuit and adapted to operate the said armatures differently, a distributor switch, a primary stepping magnet and a secondary stepping magnet for the said connector switch, each of the said magnets being adapted to operate under the control of one of the said armatures to step the connector switch wipers in the direction of the said called line under the control of the said sub-station apparatus, circuits for the said magnets selectable by the said distributor switch, an operating magnet for the said distributor switch operating under the control of other of the said armatures to shift the control of the first armature over the primary stepping magnet to the secondary stepping magnet.

7. In an automatic telephone system, the combination with a connector switch for making connection with a desired called telephone line, a primary magnet, a secondary magnet, and a controlling relay for the said switch, said relay having a pair of armatures, a calling line adapted to be associated with the said relay to control the said connector switch, a commutator for the said calling line adapted to produce successive series of calling line interruptions, one of the said armatures being responsive to each following circuit closure after each circuit interruption, the other of the said armatures being responsive only to the final prolonged closure after each series of interruptions, and to the act of associating the said calling line with the said relay, a distributor switch adapted to operate under the control of the said relay at each operation of the said other armature, an automatic interrupted machine ringing mechanism adapted to cause the ringing of the bell of the called line at definitely spaced intervals, a manually controlled ringing mecha-

1. nism adapted to cause the ringing of the said bell at and for such periods as may be desired by the calling line subscriber, said distributor switch being adapted to take 5 successive positions at each operation, the first operative position being a primary magnet operating position, the second being a secondary magnet operating position, the third being a machine ringing operating 10 position, and the fourth being a manual ringing operating position.
2. In an automatic telephone system a calling line and a called line, a link circuit interconnecting the lines, means to apply a 15 source of ringing current to the called line, an interrupter included in circuit with the said source, and means including a calling line substation apparatus adapted to subsequently substitute an alternative non- 20 interrupted circuit between the said source and the called line.
3. In a telephone system, an incoming circuit, a plurality of outgoing circuits, a numerical switch for interconnecting said incoming circuit with any of said outgoing circuits, primary and secondary operating devices for said numerical switch, switching mechanism for determining the sequence of 25 operation of said devices, a relay responsive to impulses over said incoming circuit to control the said operating devices, said relay having a plurality of armatures operating out of synchronism, one of the said armatures being actuated to cooperate with 30 said switch mechanism to control said operating devices, two of said armatures functioning to control said switching mechanism, releasing means for said numerical switch, a mechanical timing device and a controlling 35 circuit for said releasing means completed by said timing device and said relay.
4. In a telephone system, an incoming circuit, a plurality of outgoing circuits, a numerical switch for interconnecting said incoming circuit with any of said outgoing circuits, operating means for said switch, signalling means for signalling an outgoing 40 circuit, a switching mechanism for determin- 45 ing the sequence of operation of said operating means and said signalling means, a relay responsive to impulses over said incoming circuit to control said operating means, said relay having a plurality of armatures operating out of synchronism, one of said armatures being actuated to cooperate with 50 said mechanism to control said operating means, two of said armatures functioning to control said switching mechanism, releasing means for said switch, a mechanical timing device and a controlling circuit for said releasing means completed by said timing device and by said relay. 55
5. In a telephone system, an incoming circuit, a plurality of outgoing circuits, a switch for interconnecting said incoming circuit with any of the said outgoing circuits, a relay controlled over said incoming circuit and provided with a plurality of armatures operating out of synchronism to 60 control the operation of said switch, a release relay, a mechanical timing device and a release magnet co-operating in the release of said switch, an operating circuit for said release relay completed at said mechanical device and said impulse relay, a locking circuit completed thereafter for said release relay, and a circuit for the release magnet completed through contacts of said release relay and said mechanical timing device. 65
6. In a telephone system, an incoming circuit, a plurality of outgoing circuits, a switch for interconnecting said incoming circuit with any of the said outgoing circuits, a motor magnet for advancing said switch to complete desired connections, an impulse 70 relay having armatures operating out of synchronism and controlled over said incoming circuit to affect the operation of the motor magnet, release mechanism for said switch and a mechanical time measuring device cooperating with said impulse relay to control said release mechanism. 75
7. In witness whereof, I hereunto subscribe my name this 14th day of May, A. D. 1919. 80
